CLEANER

Joseph Goibach, Sacramento, Calif.

Application February 9, 1948, Serial No. 7,255

3 Claims. (Cl. 209—137)

1

This invention relates to a cleaner for rice and the like in which there is chaff to be removed from the rice.

In the handling of rice from the time it is harvested until it is hulled and ready for the market, the rice paddy or unhulled rice is usually passed through driers three times before the hulls are removed, and it is stored in large storage bins or tanks between drying steps.

The most common form of driers employ a pair of vertically extending spaced screens between which the rice paddy is positioned and progressively withdrawn from the bottom end, while heated air is forced through the screens and paddy from one of the sides of the latter.

In such driers the presence of chaff in the paddy substantially decreases the drying efficiency of the drier. The more chaff that can be removed before the paddy passes into the driers, the more efficiency will be had in the drying operation.

One of the main objects of the present invention is the provision of a simple, economical, compact cleaner adapted to be positioned over a conventional rice drier and adapted to efficiently remove the chaff from the paddy while permitting the paddy and water grass seed to pass into the drier.

The compact feature of the present invention is important in that the driers are usually quite high and a tall and bulky cleaner would not be desirable nor particularly practical if positioned on top of a drier.

Another object of the invention is the provision of a cleaner that is highly efficient in removing chaff from rice paddies without materially slowing up the feed of the cleaned paddy into the drier.

Other objects and advantages will appear in the detailed description and in the drawings.

In the drawings Fig. 1 is a side elevational view of the cleaner.

Fig. 2 is an enlarged sectional view taken along line 2—2 of Fig. 1.

Fig. 3 is a fragmentary enlarged end elevational view of a portion of one end of the cleaner as seen from line 3—3 of Fig. 1.

Fig. 4 is a reduced size fragmentary sectional view taken along line 4—4 of Fig. 2.

Fig. 5 is a fragmentary side elevational view from the same side of the cleaner as Fig. 1 except that the near side is partially broken away and the screw conveyor is indicated.

Fig. 6 is a top plan view of the cleaner.

In detail, the cleaner preferably comprises a

2

horizontally elongated housing having a top wall 1 and opposed elongated side walls 3, 4 (Fig. 2). Spaced between side walls 3, 4 and extending parallel therewith is a wall 5 and spaced between walls 4, 5 and parallel therewith is a wall 6. The walls 3, 5 define opposed sides of a feed compartment 7 while the walls 4, 6 define opposed sides of a suction compartment 8.

The opposite end walls of the above housing 10 are designated 9, 10 and form the end walls for compartments 7, 8 and for the passageway 11 that is between walls 5, 6. This passageway is for air, as will later be described more in detail.

The wall 3 is not rigidly secured to end walls 15 9, 10 but is hingedly supported by hinge 12 for swinging from its upper edge about the hinge pivot which is adjacent top wall 1.

The wall 3 is formed with an inwardly inclined intermediate portion 13 that extends toward the 20 center of the housing and a lowermost portion 14 in downward continuation of the portion 13 extends slantingly outwardly.

The wall 5 has a lowermost portion 15 that 25 slants toward the portion 13, and this portion 15 has about the same degree of slant as the portion 13, only in the opposite direction, and the upper edge of portion 15 is at the same level about as the upper edge of portion 13. The lower edges of the oppositely inwardly inclined portions 13, 15 almost meet in a plane about centrally between walls 3, 5.

Below the portion 15 is a slanted wall 16 that 30 extends between end walls 9, 10 and that is parallel with portion 15. This wall 16 has a downward continuation 17 that extends slantingly below the space 18 between the lower edges of the portions 13, 15, which lower edges define the opposite edges of an outlet from the compartment 7. Said portions 13, 15 are actually a 35 trough-like bottom in said compartment 7 and the outlet 18 constitutes an elongated variable width slot in said bottom inasmuch as the side 3 can swing toward and away from the side.

As above stated, the downward extension 40 11 extends below the outlet 18 and said extension is about parallel with and in opposed relation to the portion 14 that extends downwardly from portion 13 of wall 3.

The space between opposed portions 15, 16, 45 and the space 20 between portions 14, 17 constitute continuations of the air passageway 11, and the space 20 is also virtually a downward extension of the outlet 18 since rice discharged from outlet 18 will drop onto the portion 17 and 50 pass downwardly through passageway 20 for dis-

charge into the drier (not shown) below the cleaner housing.

Vertical ribs 21 may be secured in the re-entrant outer sides of portions 13, 14 adjacent the ends of said portions (Figs. 1, 2) and horizontal bars 22 carrying weights 23 adjustably positioned on said bars are secured to said ribs. These weights tend to hold the side wall 3 in a position in which the lower edge of portion 13 is relatively close to the lower edge of the portion 15 on side 5. The weights may be adjusted so that the outlet 18 is virtually closed when no rice or material is within the compartment 7.

A horizontally extending screw 25 extends over outlet 18, its central shaft being journalled in end walls 9, 10. Rice is fed into compartment 7 through an inlet 26 (Fig. 6) in top wall 4 adjacent one end of the compartment 7, and the rotation of the screw 25 will move the rice along the outlet for discharge therethrough, the said rice falling in a curtain or sheet on portion 17 where it rebounds and then falls into the drier. The weights 23 are adjusted to permit relief of any excess pressure in the compartment 7.

Along the upper edge of wall 6 and just below top wall 4 is a horizontally elongated air inlet opening 30 from passageway 11 into the suction compartment 8. A gate or plate 31 is secured at its upper edge to a revolvable pivot 32 that is journalled at its ends in walls 9, 10. A crank arm 33 (Fig. 3) at one end outwardly of wall 9 permits swinging of plate 31 from a vertical position closing inlet 30 into the compartment 8 and to a substantially horizontal position in which the inlet is substantially fully open.

The outer end of crank 33 may carry a wing nut 34 for releasably securing the end of the crank in arcuate slot 35 at any angular position of said arm and plate 31. Any other suitable means may, of course, be employed for releasably locking plate 31 in adjusted position.

The said inlet 30 extends substantially from wall 9 to wall 10 so that suction is effective within the passageway 11 from end to end thereof upon suction being created in compartment 8.

A suction blower 37 is positioned alongside wall 4 with its central annular suction inlet 38 opening into wall 4 about centrally between the ends of the latter and spaced below top wall 4. The outlet 39 of this blower may exhaust to the atmosphere or to a stack or collector, as desired.

The bottom wall 40 of compartment 8 extends slantingly downwardly from end walls 9, 10 respectively to meeting relation along the lower edge of the blower inlet 38. Thus movement of any material on said bottom to the blower inlet is facilitated.

A motor 41 supported on a bracket 42 or on an extension of top 4 may drive both the blower and the screw, a belt 43 extending from a pulley on the motor shaft to a pulley on the blower shaft while a belt 44 may extend from a pulley on the blower shaft to a pulley on the driving shaft of a reduction gear box 45. The slow driven shaft from said box may be connected by a belt 46 with a pulley on the screw shaft.

A substantially air tight lid 47 may cover an opening 48 in top 4 to enable access to the air passageway and to compartment 8 and to the gate 31.

In operation, when the motor 41 is actuating the blower and screw, upon feeding the rice paddy into compartment 7, said paddy will fall through outlet 18 and into the influence of the air suction in passageway 11.

The gate 31 is so adjusted relative to the volume of flow of paddy that substantially all of the chaff will be drawn upwardly into the suction compartment for discharge from the blower discharge side, while the rice paddy and water grass seed will fall into the drier.

Some of the chaff may tend to be carried down by the paddy but upon the rice rebounding off the portion 17 this chaff will be loosened or separated from the rice for being drawn into the suction chamber.

While all of the chaff may not be removed from the rice paddy the first time it goes through the cleaner, as a rule all of the chaff is removed by the time the rice passes through the cleaner for the third time. Of course any other materials mixed with the rice paddy having about the same specific gravity as the chaff will be drawn into the suction compartment for discharge.

I claim:

1. A cleaner for rice and the like comprising a housing enclosing a horizontally elongated air suction compartment and a horizontally elongated feed compartment in side by side relationship, an outlet in the bottom of said feed compartment extending substantially the full length thereof and a similarly extending inlet opening into the upper portion of said air suction compartment, an air passageway between said suction compartment and said feed compartment communicating between said outlet and said inlet, means for creating a suction within said suction chamber, and said passageway having a downward extension continuing downwardly past said outlet for receiving a supply of air therethrough, said extension having an open lower end for discharge of material not drawn into said suction chamber, a horizontally extending screw conveyor in said feed chamber extending over said outlet for moving rice to different points along said outlet, the lower portion of one of the side walls of said feed compartment being one side of said outlet, and means hingedly supporting said portion for swinging toward and away from the opposite side of said outlet for varying the size of the latter, and means secured to said portion tending to constantly urge said portion toward the said opposite side of said inlet against the outward pressure of material passing through said outlet.

2. A cleaner for rice and the like comprising a housing enclosing a horizontally elongated air suction compartment and a horizontally elongated feed compartment in side by side relationship, an outlet in the bottom of said feed compartment extending substantially the full length thereof and a similarly extending inlet opening into the upper portion of said air suction compartment, an air passageway between said suction compartment and said feed compartment communicating between said outlet and said inlet, means for creating a suction within said suction chamber, and said passageway having a downward extension continuing downwardly past said outlet for receiving a supply of air therethrough, said extension having an open lower end for discharge of material not drawn into said suction chamber, said means for creating said suction being a rotary suction blower having its central air inlet disposed at a point about centrally between the ends of said suction compartment, said suction compartment having a bottom wall extending slantingly upwardly from said central air inlet to said opposite ends of said

compartment to facilitate downward movement of material on said bottom wall to said central air inlet.

3. A cleaner for rice and the like comprising a housing enclosing a horizontally elongated air suction compartment and a horizontally elongated feed compartment in side by side relationship, an outlet in the bottom of said feed compartment extending substantially the full length thereof and a similarly extending inlet opening into the upper portion of said air suction compartment, an air passageway between said suction compartment and said feed compartment communicating between said outlet and said inlet, means for creating a suction within said suction chamber, and said passageway having a downward extension continuing downwardly past said outlet for receiving a supply of air therethrough, said extension having an open lower end for discharge of material not drawn into 20 said suction chamber, said means for creating said suction being a rotary suction blower having its central air inlet disposed at a point about centrally between the ends of said suction compartment, said suction compartment having a 25 bottom wall extending slantingly upwardly from

said central air inlet to said opposite ends of said compartment to facilitate downward movement of material on said bottom wall to said central air inlet, means for adjustably controlling the air passing from said passageway into said suction compartment comprising a plate movable different distances to and from a position closing said inlet into said suction compartment, and means for releasably holding said plate in adjusted position.
